UNITED STATES PATENT OFFICE.

PHILIP H. LETTRÉ, OF ATTLEBORO FALLS, MASSACHUSETTS.

BOX-FASTENER.

1,076,897.

Specification of Letters Patent.

Patented Oct. 28, 1913.

Application filed April 24, 1913. Serial No. 763,380.

To all whom it may concern:

Be it known that I, PHILIP H. LETTRÉ, a citizen of the United States, residing at Attleboro Falls, in the county of Bristol and State of Massachusetts, have invented a new and useful Box-Fastener, of which the following is a specification.

This invention relates to box fasteners.

An object of the present invention is to provide an improved form of box fastener which is adapted to fasten and hold securely in place the flaps of a box.

A further object is to provide a fastener especially adaptable for boxes to be used in connection with the parcel post whereby the box may be used a number of times, the fastener being such that the flaps are held rigidly and securely in place and at the same time provide easy and readily accessible means for the disengaging of the box flaps for the opening thereof.

A further object is to provide a metallic fastener rigidly secured to one flap of a box and adapted to engage the other two flaps and to hold the same in closed position.

With the foregoing and other objects in view which will appear as the description proceeds, the invention résides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereto the preferable form of my invention is illustrated, in which:

Figure 1 is a view in perspective, illustrating the first step in securing my improved fastener to the flaps of a box. Fig. 2 is a view in perspective of the box in a partially closed position. Fig. 3 represents in perspective the box in a closed position and the fastener rigidly secured thereto and holding the box flaps closed. Fig. 4 represents the blank forming my improved fastener. Fig. 5 represents in perspective the fastener prior to inserting the same through the flaps of a box. Fig. 6 represents the fastener as it appears in the box prior to the closing of the flaps as illustrated in Fig. 2.

Referring to the drawings in which similar reference numerals designate correspond-

ing parts throughout the several views, 1 represents the body portion of a box or receptacle which is provided with the four closing flaps. The said flaps are arranged in pairs and are spoken of as the transverse flaps 2 and the longitudinal flaps 3, the terms used being merely relative and employed to bring out more clearly the applicant's device.

As illustrated in the drawings, the improved box fastener is to be used with boxes provided with closing flaps secured to the side and end walls, the fastener in question being rigidly secured to the under flap and adapted to engage and hold rigidly thereto the two flaps which close down thereupon.

The fastener comprises a blank as illustrated in Fig. 4 and includes the base 4, the restricted portion 5, termed the neck and integral with which is the top or head portion 6. The base 4 is adapted to bend along the dotted lines 7 to thereby form the wings 8 which are adapted to pierce the under flaps of the box or receptacle and to bend therearound as illustrated in Fig. 6, from which it will be apparent that the flaps 2 will be rigidly engaged between the main portion of the base 4 and the wings 8 which are bent upon themselves substantially as illustrated.

The fastener is first installed with the wings 8 piercing the flaps 2 of the receptacle and which wings are then bent upon themselves to hold the fastener rigid to the flaps as illustrated in Fig. 1. The flap 2 is then brought downwardly into its closed position and the head 6 of the fastener is then bent upwardly along the dotted lines 9 of the neck to thereby assume the position substantially as illustrated in Figs. 2 and 6 of the drawings, at which time the top or overlying flaps 3 are brought downwardly and inserted between the head and base of the flap and contact with the neck of the fastener to thereby be securely held within the restricted passage defined by the base and the head which is offset therefrom. In the position as illustrated in Fig. 2 of the drawings one of the over flaps 3 is positioned in the restricted passage just mentioned. The other flap 3 is brought down into a similar position after which the heads 6 are bent downward along the dotted lines 10 to the position substantially as illustrated in Fig. 3 which is the final position and the head 6

which is substantially triangular in outline overlies the meeting edges of the over flaps and holds the same in rigid relation to the under flaps with the result that an efficient 5 and rigid fastener is obtained. The said box fastener is preferably made from sheet metal so that the same may be readily bent to the shape desired and the metal used in the construction thereof so selected that the 10 fastener may be used and bent into its closed and open position a successive number of times without liability of the same becoming broken or cracked.

From the foregoing it will be apparent 15 that my improved box fastener is adapted to rigidly secure the flaps of a box or receptacle in a closed position and maintain the same rigidly so positioned. The fastener is particularly adaptable to those boxes which are 20 to be used a number of times in connection with the parcel post and other transporting means, in which case it is to be noted that the fastener having been once rigidly secured to the under or transverse flap 2 is 25 not disturbed with relation to this flap but have the wings 8 crimped down upon the under surface of the flap in a rigid manner and remains in this position. When it is desired to open the box from the position illus- 30 trated in Fig. 3, the head 6 of the fastener is first bent upwardly and the longitudinal or overlying flaps 3 may then be brought upwardly and at the same time retracted from the center portion of the box to bring 35 the same out of the restricted passages defined by the base 4 and the head 6 which

is spaced a distance therefrom by means of the neck 5 which is of a limited length.

From the foregoing it will be apparent 40 that a number of the fasteners such as I have described may be used upon each and every box, the exact number depending upon the size of the box in question and the strength of the fasteners. The triangular 45 form of the head of the fastener provides that the vertices thereof will overlie the upper flaps and contact with sufficient surface thereof to obtain a rigid purchase thereon.

Having thus fully described the invention 50 what I claim to be new and original with me is:

In a device of the class described the combination with a receptacle having upper and lower flaps, of a fastener comprising a base 55 with wings extending through the under flap and bent into engagement therewith, a restricted neck projecting from said base, a head connected to said neck, the restricted notches defined by the head and base receiv- 60 ing the upper box flaps therein, said head bent at right angles to the said neck and into contact with the upper surface of said upper flap to securely hold said flaps in a closed position and in rigid relation. 65

In testimony that I claim the foregoing as my own, I have hereto affixed my signature in the presence of two witnesses.

PHILIP H. LETTRÉ.
